4 Claims. (Cl. 336—110)

1

This invention relates to a coil assembly with variable premagnetization.

The main object of the invention is to provide a magnetic coil having a ferromagnetic core and means for providing smooth and accurate control of the premagnetization of the core.

This and other objects of the invention will be best understood from the following description.

According to the invention, the coil assembly includes a permanent magnet spaced from the main core. Both the core and the magnet are adapted to be moved relative to each other to vary the spacing therebetween. With such an arrangement, the premagnetization of the core can be accurately adjusted.

In a preferred embodiment, a rod-like magnet is arranged parallel to the ferromagnetic core of a coil winding and is secured to a cylindrical support of non-magnetic material adapted to rotate about its longitudinal axis thereby altering the spacing between the magnet and the ferromagnetic core and, consequently, the degree of magnetization of the core.

The invention will now be described with reference to the accompanying drawing in which:

Fig. 1 is a view, in cross-section, of one form of magnetic coil in accordance with the invention;

Fig. 2 is an end view of the coil shown in Fig. 1;

Fig. 3 is a diagrammatic representation of the coil shown in Fig. 1 showing how a smooth control of premagnetization of the core is obtained;

Figs. 4 and 5 are simplified views of the coil shown in Fig. 1 illustrating the need for maintaining the parallel relationship between the magnet and the core.

Referring to Figs. 1 and 2, the coil assembly comprises a winding 1 and a rod-like ferromagnetic core 3 which may consist of cubic mixed crystal ferrite, of the type described in U. S. Patents 2,452,529, 2,452,530 and 2,452,531 to J. L. Snoek issued. The winding 1 with its core 3 is secured in position in a suitable cylindrical bore 5 in a housing 7 of non-magnetic material, e. g., a synthetic resin.

A second cylindrical bore 9, adjacent to and above the bore 5, extends lengthwise through the housing 7 and is parallel to the bore 5. A cylindrical support 11 of non-magnetic material, e. g., synthetic resin, is journaled in the bore 9 and is adapted to be rotated within said bore about its longitudinal axis. A rod-like permanent magnet 13 is secured to the support 11 in a manner such that it is eccentric with respect

2

to a center axis of the support 9 and substantially parallel thereto and to the core 3. A slot 15 is provided on one of the end faces of the support 11 so that it may be rotated by means of a screw driver.

The magnetic field produced by the permanent magnet 13 is partly closed through the ferromagnetic core 3, resulting in premagnetization of the core 3. The intensity of the premagnetization naturally varies with the spacing between the core 3 and the permanent bar magnet 13. It is obvious that rotating the cylindrical support 11 about its longitudinal axis causes the said spacing to vary and thus enables the premagnetization of the core 3 to be varied.

In the position in which the core 3 and the magnet bar 13 are closest to one another (diagrammatically shown in Fig. 3) the magnetization is a maximum, in which case, the core 3 will generally be saturated. In this position, a given variation in spacing between the core and the magnet is found to have a greater effect on the resultant magnetization of the core than in the positions in which the spacing is larger. In other words, the sensitivity of control for different spacing between the core and the magnet is not constant. However, as shown in Fig. 3, this difference in sensitivity is compensated for by the circular movement of the magnet 13. In this figure, a, b, and c designate three positions which the magnet 13 occupies in relation to the core 3 when the support 11 (Fig. 1, not shown in Fig. 3) is turned twice in succession through the same angle. As may be seen from the figures, the variation in distance a'b' which results from the first angular rotation is much smaller than the variation b'c due to the second rotation. Consequently, a substantially constant sensitivity of control and, hence, a smooth control is thus obtained.

Figs. 4 and 5 demonstrate the importance of the opposed parallel position of the core 3 and magnet rod 13. Fig. 4 shows that in this parallel position the lines of force which emanate from the magnet 13 will enter the core 3 primarily at the ends of the core outside the wound part or coil 1. The magnetization is, consequently, substantially constant in the wound part of the core. If, however, as shown in Fig. 5, the rod 13 is inclined relative to the core 3, part of the flux will, as shown in the figures, enter the core through the winding 1 adjacent those ends of the core and magnet which are remote from each other (at the right of Fig. 5), because at this point the distance is less than at the in-

volved ends themselves. This results in the wound part of the core 3, which is furthest to the right, being less saturated than the remaining part, and that the part of the coil which corresponds to the said part has an induction different from that of the saturated part. This constitutes a disadvantage which can be obviated by a permanently substantially opposed parallel position of the core and the magnet.

In view of the above, it is also important that the magnet 13 not be excessively short compared with the coil 1 since with an excessively short magnet, lines of force will again pass laterally through the winding, and as explained before, this is undesirable. In practice, it is satisfactory if the rod is longer or at least not shorter than the wound part of the core and that these two elements are directly opposite one another.

While the invention has been described in connection with specific examples and in specific application, other modifications thereof will be readily apparent to those skilled in the art without departing from the invention as defined in the appended claims.

What I claim is:

1. A coil assembly comprising a housing of non-magnetic material, a coil within said housing, a rod-like core of ferromagnetic material within said coil, a cylindrical member of non-magnetic material rotatably supported within the housing, and a permanent magnet eccentrically secured to said cylindrical member and extending opposingly parallel to and spaced from said core for varying the spacing between the core and the permanent magnet to thereby alter the premagnetization of said core upon rotation of said cylindrical member.

2. A coil assembly comprising a housing of non-magnetic material, a coil within said housing, a rod-like core of ferromagnetic material within said coil, a cylindrical member of non-

magnetic material arranged parallel to said core within said housing, and a permanent magnet secured to said cylindrical member and arranged parallel to the axis of the cylindrical member for varying the spacing between the core and the permanent magnet to thereby alter the premagnetization of said core upon rotation of said cylindrical member.

3. A coil assembly comprising a housing of non-magnetic material, a coil within a portion of said housing, a rod-like core of ferromagnetic material within said coil, a cylindrical member of non-magnetic material journaled within a second portion of said housing and parallel to said coil, and a permanent magnet supported by and arranged parallel to the axis of said cylindrical member for varying the spacing between the core and the permanent magnet to thereby alter the premagnetization of said core upon rotation of said cylindrical member.

4. A coil assembly comprising a housing of non-magnetic material, a coil within said housing, a rod-like core of ferromagnetic material having a given length within said coil, a cylindrical member of non-magnetic material journaled in said housing, and a permanent magnet having a length at least equal to said given core length supported by and arranged parallel to the axis of said cylindrical member for varying the spacing between the core and the permanent magnet to thereby alter the premagnetization of said core upon rotation of said cylindrical member.
